(57) CLAIM

I claim the ornamental design for a bottle, as shown and described.

DESCRIPTION

FIG. 1 is a perspective view of the present invention;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view.

The shade lines applied to the bottle throughout the drawing views indicate the contours of the bottle. The evenly-dashed broken lines in the drawings showing of the closure illustrate the portions of the design that form no part of the claim.
